UNITED STATES PATENT OFFICE.

JOSEPH EDWARDS, OF BROOKLYN, NEW YORK.

DUMPING-SCOW.

SPECIFICATION forming part of Letters Patent No. 408,298, dated August 6, 1889.

Application filed December 21, 1888. Serial No. 294,338. (No model.)

To all whom it may concern:

Be it known that I, JOSEPH EDWARDS, a citizen of the United States, residing in the city of Brooklyn, county of Kings, and State 5 of New York, have invented a new and useful Improvement in Dumping-Scows, of which the following is a specification.

My invention relates to the method of holding, operating, and rendering tight-fitting the 10 dumping-doors of that class of dirt-scows which discharge their cargoes through a series of ports or openings in the bottom thereof, and especially those of such scows as are employed for handling fine sea-sand more or 15 less mixed with water. It is found in practice that when fine sea-sand mixed with water is pumped into scows difficulty is encountered in rendering these discharging ports or doors sufficiently tight to hold the 20 sand, which must be water-tight to prevent the escape of sand. It is also found that when the scows are thus freighted with fine sea-sand these discharging-doors will not open to discharge the cargo, owing to the fact that the 25 sand becomes so compacted and consolidated that it is rendered immobile, and, for the same reason, it also cuts off the downward atmospheric pressure, which prevents these 30 dump-doors from opening unless they be forced downward by other means than gravity, which is not the case with the handling of ordinary dirt and mud. Besides, when chains are employed to hold the doors the compacted 35 wet sand prevents the chains from sliding through it.

The object of my improvement is to obviate this difficulty and to provide means for controlling the operation of the dumping-doors and rendering them water-tight, which I 40 accomplish by the device illustrated in the accompanying drawings, in which—

Figure 1 represents a partial longitudinal elevation of the interior of the scow, showing two of the series of the dump-doors and the 45 device for operating them; Fig. 2, a partial transverse elevation showing the same; Fig. 3, a plan view of one of the dump-doors and the hinges by which it is attached to the bottom of the scow; Fig. 4, a modification of a 50 part of the means of operating the dump-doors, and Fig. 5 also a modification of a part of the means of operating the dump-doors.

Similar letters refer to similar parts throughout the several views.

A A represent ports or dump-openings in 55 the bottom of the scow between the framework A' A' of the scow.

B B is the bottom of the hopper, which terminates far enough above the bottom of the scow to form a recess to receive the dump-door 60 D D, so that the door, when closed, will be flush with the bottom of the scow, and which furnishes a horizontal face or jamb for the door to close against.

F F are hinges connecting one side of the 65 door D D to the bottom of the scow.

E E is a heavy strip of yielding rubber fastened on all sides of the bottom of the hopper B B for the dump-door D D to strike against to insure a water-tight fit.

C is a connecting-rod between the door D D and the sliding screw-rod G G. This connecting-rod C is fastened at the bottom end to the top of the dump-door D D by means of a working joint c c and c' and at the top end by a 75 working joint d to the sliding screw-rod G G. The screw-rod G G passes through the deck H' H' of the scow, upon which it is mounted in the frame H H.

I I is a casting bolted to the frame-work H H, i i being a packed sleeve which guides and holds the rod G G and through which it slides. Upon the top of the frame H H is also fastened a similar casting i' i', through which the rod G G passes, and upon the casting i' i' is 85 bolted a casting J, into which is fitted a rotating threaded nut I, that works upon and operates the screw-rod G G. To this nut I is fastened a large wheel with which to rotate the nut I. (Represented by K K.)

Fig. 4 represents a modified method of working the rod G G without a thread and nut, which may be accomplished by a pinion working in corresponding cogs on one side of the said rod G G, as illustrated.

Fig. 5 represents another modified method of working the rod G G, which is by means of water-pressure in acting upon a piston attached to the rod G G and actuated by the pressure of water within the corresponding 90 cylinder.

Having described the various parts of my device and the functions thereof, the general explanation of the operation of my invention

is briefly explained as follows: The dumping-doors D D are represented in the drawings as closed, in which position they are held by the connecting-rod C, which is held by the screw-rod G G, which said rod is vertically held and controlled in both the upward and downward direction by the rotating nut I, which said nut is operated by the wheel K K. When the scow is to be discharged of its cargo, the screw-rod G G is run down by rotating the nut I by rotating the wheel K K, which drives the connecting-rod C downward, which accommodates itself to the swinging motion of the door D D, and which forces the said door open. When the cargo is discharged, the said doors are again closed by rotating the nut I in the opposite direction and thus running up the screw-rod G G, and by the action and power of the screw forcing the door D D so firmly against the rubber strips E E as to make a perfectly water-tight fit between the said door and the bottom of the hopper B B.

I am aware that revolving nuts and screw-rods have been employed for operating conic valves in dumping-scows in such a manner that the screw-rod and conic valve constitute one rigid structure. Therefore I do not claim, broadly, the use of a screw-rod and rotating nut for operating dumping-scow valves; but what I do claim as new and useful, and desire to secure by Letters Patent, is—

1. In a dumping-scow, the combination of the rigid sliding rod G G, connecting-rod C, and swinging dump-door D D, the upper end of the said connecting-rod being fastened to the lower end of the said sliding rod, and the lower end of the said connecting-rod being fastened to the upper side of the said dump-door, whereby the dump-door can be forced open or closed by the vertical movement of the laterally-rigid rod, in the manner and for the purpose set forth.

2. In a dumping-scow, the combination of the rigid sliding rod G G, having a screw-thread and a vertically-stationary threaded nut I thereon, connecting-rod C, and swinging dump-door D D, the said connecting-rod having its upper end fastened to the lower end of the said sliding rod and its lower end attached to the upper side of the said dump-door, whereby the rotating of the said nut will give a vertical movement to the sliding rod and force down or draw up the connecting-rod and open or close the dump-door, according to the direction in which the said nut is rotated, substantially as and for the purpose described.

JOSEPH EDWARDS.
